CLAIM

The ornamental design for a stand for an electronic device, as shown and described.

DESCRIPTION

FIG. 1 is a front perspective view of a stand for electronic device, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view thereof shown in a first position of use;

FIG. 10 is a rear perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a perspective view thereof shown in a second position of use;

FIG. 16 is still another perspective view of FIG. 14;

FIG. 17 is a view identical to FIG. 9, and shown in the environment of an electronic device; and,

FIG. 18 is a view identical to FIG. 1, and shown in the environment of an electronic device.

The broken lines in FIGS. 17 and 18 illustrate environment and portions of the stand for electronic device. The broken lines in the remaining views illustrate portions of the stand for electronic device. None of the broken lines form part of the claimed design.

1 Claim, 18 Drawing Sheets
